CLAIM

The ornamental design for a magnet cell phone ring stand, as shown and described.

DESCRIPTION

FIG. 1 is a perspective view of a magnet cell phone ring stand showing our new design in a first position;
FIG. 2 is another perspective view thereof;
FIG. 3 is a front elevation view thereof;
FIG. 4 is a back elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a perspective view of the magnet cell phone ring stand of FIG. 1 shown in a second position;
FIG. 10 is a perspective view of the magnet cell phone ring stand of FIG. 1 shown in a third position; and,
FIG. 11 is an enlarged view of the encircled portion in FIG. 2.

The equal-length broken lines depict portions of the magnet cell phone ring stand that form no part of the claimed design. The dash-dot broken lines in FIG. 2 and FIG. 11 illustrate the boundaries of the enlarged view indicators and form no part of the claimed design.
